UNITED STATES PATENT OFFICE.

HALVOR E. HOINES, OF MINNEAPOLIS, MINNESOTA.

GRAIN-CLEANING MILL.

1,088,577.

Specification of Letters Patent. Patented Feb. 24, 1914.

Application filed July 29, 1913. Serial No. 781,812.

To all whom it may concern:

Be it known that I, HALVOR E. HOINES, a subject of the King of Norway, residing at Minneapolis, in the county of Hennepin 5 and State of Minnesota, have invented certain new and useful Improvements in Grain-Cleaning Mills, of which the following is a specification.

The present invention relates to improvements in grain cleaning mills, the object in view being to provide an auxiliary cleaning member by which certain characters of foreign seed or matter may be removed from the grain as it flows from one grading 15 sieve to another. To this end I provide a conveyer member disposed in the path of flow of the grain and upon which the grain falls, said conveyer comprising an endless apron of unfinished fabric designed particu- 20 larly to catch the lighter or foreign seeds in the grain not removed by the usual blast.

It is furthermore an object of my construction that the conveyer operate in a direction opposite the flow of the grain for 25 conveying the foreign seed to a point where it may be removed by a conveyer cleaner disposed in a position to coöperate with the conveyer aforesaid.

Still a further object of the invention is 30 to provide means for insuring that the grain will not pass over the edges of the conveyer in its passage thereover.

With these and other objects in view, my invention consists of certain combinations, 35 constructions, and arrangements of parts, all as hereinafter more fully described, claimed and illustrated in the accompanying drawings, wherein

Figure 1 is a side elevation of a fanning 40 mill constructed in accordance with my invention; Fig. 2 is a detail perspective view of the fabric conveyer coöoperating with the grading sieves; Fig. 3 is a detail perspective view of the conveyer cleaner; Fig. 4 is 45 a fragmentary front view of the locking means for operably connecting the conveyer cleaner for operation; and Fig. 5 is a similar view showing more clearly the locking means in side elevation.

Throughout the following detail description, and on the several figures of the drawings, similar parts are referred to by like reference characters.

Specifically describing my invention, the 50 numeral 1 designates a frame of suitable form and construction having secured at

the top portion of the same the grain hopper 2. The hopper 2 is of the usual construction and the grain is designed to flow from the same upon the shaking or reciprocating sieve 3 connected at one end to the hopper by means of the link 4 and supported near its opposite end by the shaker arm 5 pivoted intermediate its length upon the transverse frame member 6, said arm having connected to its lower end the connecting rod 7, which is in turn connected to the sprocket wheel 8 fixedly secured upon the shaft of the fan 9 mounted in the usual fan drum 10.

It is to be noted that the reciprocating sieve 3 inclines downwardly from the hopper and from its lower end the grain to be cleaned drops into a V-shaped chute 11 through which it passes onto the endless 15 conveyer 12 disposed at an abrupt incline in a direction opposite to the incline of the sieve 3 and near the upper portion of the lower stationary inclined grading sieve 13. The conveyer 12 is mounted for movement 20 about the roller 14 secured in the sides of the inclined sieve 13 and the upper roller 15 supported by means of the arms 16. The conveyer is composed preferably of an unfinished fabric and stretched tightly about 25 the rollers, movement being imparted to said conveyer by means of the driving chain 30 which passes around the sprocket 18 on the shaft 19 to which is also secured the pinion 20 intermeshing with the large pinion 21 secured to the end of the roller 15, said driving chain 35 passing around the sprocket 8 for imparting rotary motion to the fan 9 in the usual manner, as well as reciprocating motion to the sieve 3 through 40 the medium of the connecting rod 7 and the shaker arm 5, said chain being driven by the sprocket 17.

On the shaft 19 is provided a conveyer cleaner consisting of a plurality of blades 45 arranged so as to contact with the conveyer 12 when rotated by the driving chain 50 passing around the sprocket 18.

In the use of the invention it will be understood that the mill is operated by revolving 55 the driving sprocket 17 to which is secured a handle 23, the grain passing from the hopper 2 onto the shaker sieve 3, and from said sieve through the chute 11 onto the conveyer 12, the lighter foreign matter being separated 60 during its passage to this point by means of the blast from the fan 9, said blast, however,

not being sufficient to remove, ordinarily, certain characters of foreign seed, such for instance as wild oats, which are caught by the fabric conveyer 12 before the grain 5 reaches the lower grading sieve 13 from which it passes in the cleaned condition. The conveyer 12 moves in a direction opposite to the flow of the grain to the sieve 13 and as it passes around the roller 15 the 10 blades 22 impinge against the conveyer and remove the foreign seed therefrom.

In order to prevent the grain from passing laterally off of the conveyer 12 I provide a longitudinally curved guard plate 24 15 secured at each side of the conveyer to the sides of the sieve 13, as most clearly shown in Fig. 2 of the drawing. The guard plate 24, by reason of its curved inner face, turns upwardly the edges of the upper portion of 20 the conveyer 12 and this tends to keep the grain upon said conveyer until it passes therefrom onto the sieve 13.

Under certain conditions it may be desired to disconnect from operation the conveyer cleaner on the shaft 19 and for this 25 purpose I have provided the shaft 19 with an enlarged extremity 19' having a notch 19'' in its periphery. To the sprocket wheel 18 is secured a leaf spring 25 bearing at its 30 free end against a pawl 26 pivotally mounted upon the pin 27 carried by said sprocket wheel. When the pawl 26 is in its horizontal position, shown most clearly in Fig. 5 in full lines, it engages in the notch 19'' on the 35 shaft 19 and the conveyer cleaner is thus connected for operation by the driving chain 17. When, however, the pawl 26 is raised, the spring 25 holding said pawl in either of its positions hereinbefore mentioned, the 40 sprocket wheel 18 which is loosely mounted upon the shaft 19 disconnects the conveyer cleaner. The disengagement of the pawl from the notch not only disconnects the conveyer cleaner as hereinbefore described but 45 also prevents operation of the conveyer 12 which is rotated through the medium of the pinion 20 carried by the shaft 19.

It will be apparent from the foregoing description that the grain will not only be 50 cleaned of the general foreign matter of a lighter character than the grain but also the

foreign seeds which are contained by said grain will adhere to the conveyer and be effectively removed during the grading operation of the grain.

Having thus described the invention, what I claim as new is:—

1. In a cleaning mill, the combination of a grain hopper, grading sieves for assorting the grain, blast means for cleaning the grain, a conveyer member for catching and removing foreign seed from the grain, said conveyer member operating in a direction opposite to the flow of said grain, a conveyer cleaner for removing foreign seed from the 65 conveyer, a shaft for said cleaner, gearing connecting the shaft with the conveyer, common operating means for the blast means, the conveyer, and conveyer cleaner, including a drive sprocket on the shaft aforesaid, and means for connecting or disconnecting the sprocket with or from the shaft to thereby operate or render inoperative the conveyer member and conveyer cleaner.

2. In a cleaning mill, the combination of a hopper, a shaking sieve to receive the grain from the hopper, a blast member for cleaning the grain flowing over the shaking sieve, a fabric conveyer adapted to receive the grain from the shaking sieve, means for operating said conveyer in a direction opposite the flow of the grain, said means also operating the blast member and shaking sieve, a stationary grading sieve adapted to receive the grain from the conveyer aforesaid, a guard plate coöperating with the edges of the conveyer, a conveyer cleaner disposed beneath the conveyer, a shaft upon which said cleaner is mounted, a sprocket wheel carried by said shaft, and a locking member carried by the sprocket wheel and adapted to engage the shaft to permit operation of the conveyer cleaner by the operating means for the blast and conveyer aforesaid.

In testimony whereof I affix my signature in presence of two witnesses.

HALVOR E. HOINES.
